CLAIM

I claim an ornamental design for a card reading and writing apparatus, as shown and described.

DESCRIPTION

FIG. 1 is a front perspective view of the card reading and writing apparatus of the present invention;

FIG. 2 is a front view of the card reading and writing apparatus of the present invention;

FIG. 3 represents a rear view of the card reading and writing apparatus of the present invention;

FIG. 4 represents a right side view of the card reading and writing apparatus of the present invention;

FIG. 5 represents a left side view of the card reading and writing apparatus of the present invention;

FIG. 6 represents a top view of the card reading and writing apparatus of the present invention; and,

FIG. 7 represents a bottom view of the card reading and writing apparatus of the present invention.

The broken-line disclosure in the views are understood to represent portions of the article in which the claimed design may be embodied, but which forms no part of the claimed design.
